QUESTION AND ANSWER GAME DISC DEVICE

Abraham L. Kamen, 311 Beach 147th St., Neponsit, N.Y.

Filed June 21, 1961, Ser. No. 65,671

Term of patent 3½ years

(Cl. D35—5)

FIG. 1 is a plan view of a question and answer game disc device showing my new design; and

FIG. 2 is an edge view thereof.

The dominant features of my design reside in the portions shown in full lines and is characterized by the spread-legged clown figure above the rotating disc having two sets of three indicating apertures in a vertical in-line relationship, all as shown.

I claim:

The ornamental design for a question and answer game disc device, as shown and described.
